UNITED STATES PATENT OFFICE

RALPH T. OWEN, OF SPRINGFIELD, ILLINOIS.

DESIGN FOR A VACUUM-CLEANER FRAME.

43,011.

Specification for Design.

Patented Sept. 10, 1912.

Application filed April 8, 1912. Serial No. 689,436. Term of patent 7 years.

To all whom it may concern:

Be it known that I, RALPH T. OWEN, a citizen of the United States, residing at Springfield, in the county of Sangamon and State of Illinois, have invented a new, original, and ornamental Design for Vacuum-Cleaner Frames, of which the following is a specification, reference being had to the accompanying drawing, forming part thereof.

The figure is an isometric view of a

vacuum cleaner frame showing my new design.

I claim—

The ornamental design for a vacuum cleaner frame as shown.

RALPH T. OWEN.
